UNITED STATES PATENT OFFICE.

PHILIP LIBONATI, OF NEW YORK, N. Y.

BOX-OPENER.

1,090,316.

Specification of Letters Patent. Patented Mar. 17, 1914.

Application filed November 26, 1912. Serial No. 733,660.

To all whom it may concern:

Be it known that I, PHILIP LIBONATI, a citizen of the United States, residing at New York, in the county of New York and State 5 of New York, have invented certain new and useful Improvements in Box-Openers, of which the following is a specification.

This invention relates to box openers, and is designed more particularly for the purpose of lifting the lid of a box of shoe polish so that the lid may be readily removed by hand.

The boxes containing shoe polish are generally fitted with a practically air-tight 15 cover, the purpose being to prevent evaporation or deterioration of the contents of the box. These lids are tightly fitted to the boxes and can not be readily removed by hand, without being first loosened or lifted. 20 One of the principal objects of my invention is to provide reliable and efficient means for lifting or starting the cover at two points of contact upon one side of the cover.

Another object of the invention is to provide inexpensive means pivotally connected to the box for loosening the cover, said means lying close to the box, and entirely out of the way when not required for use, and which can be quickly operated for 30 loosening the cover.

These and other objects may be attained by means of the construction illustrated in the accompanying drawing, in which:

Figure 1 is a perspective view of a box 35 of the usual construction designed for containing shoe polish, said box having pivotally connected thereto an opener made in accordance with my invention. Fig. 2 is a side elevation of the same showing the 40 opener in full lines in position for packing and shipping, and when not required for use, and in dotted lines showing the lid lifted slightly from the box by the opener. Fig. 3 is a sectional plan view of the opener 45 pivoted to a portion of the box. Fig. 4 is a detail perspective view of one of the members of the opener.

Referring to the drawing the numeral 1 designates the box designed for containing 50 shoe polish, 2 is the cover for said box. As usually constructed the covers for these

boxes are provided with an outwardly extending flange 3, but it will be understood that my opener may be used for lifting a lid provided with a plain unflanged edge. 55

The opener comprises two members or levers 4, said levers being pivoted upon a pin or stud 5 extending through holes 6 in the members 4. The upper ends of the members 4 are each provided with a curved 60 or rounded bearing portion 7; extended beyond said bearing portion is a lip 8. At the opposite ends the members 4 are each provided with an outwardly extending finger-hold 9. 65

It will be seen upon reference to Fig. 3, that the members 4 may be curved to conform to the contour of the box.

The operation of my invention may be readily understood from the foregoing. 70

When the members 4 are in the position shown in Fig. 1 the finger-holds 9 are engaged by the thumb and finger, and pressed together to the position shown in Fig. 2, the rounded bearing portions 7 riding freely 75 under the cover for lifting the same and bearing at two separate points against said cover.

From the foregoing it will be obvious that my invention is of simple construction, can 80 be manufactured at low cost, is reliable and efficient in operation, and can be connected to any form of box requiring extraneous means for loosening or lifting the cover.

I claim:

A box opener comprising two levers having enlarged and flattened portions pivotally connected to the body of the box underneath the cover, said levers being curved to conform to the contour of the box, said levers 90 each having a rounded bearing portion to engage the lower edge of the box cover and a lip extending beyond the bearing portion to engage the outer edge of the flange of the box cover, said levers each having an 95 outwardly projecting finger-hold. 85

In testimony whereof I have affixed my signature in presence of two witnesses.

PHILIP LIBONATI.
